UNITED STATES PATENT OFFICE.

HARRY K. VON DER HEYDT, OF BUTTE, MONTANA.

DENTAL APPLIANCE.

Application filed September 25, 1922. Serial No. 590,462.

To all whom it may concern:

Be it known that I, HARRY K. VON DER HEYDT, a citizen of the United States of America, and resident of Butte, in the county 5 of Silver Bow and State of Montana, have invented certain new and useful Improvements in Dental Appliances, of which the following is a specification.

This invention relates to the art of dentistry, and particularly to trays adapted for use in holding casts or forms having impressions in mechanical dentistry.

Heretofore, the impressions for the upper jaw and the lower jaw have been trimmed by hand in shaping and smoothing them to the required degree, and this necessitated a very great expenditure of time and labor.

It is an object of this invention to produce a tray or holder preferably made of celluloid into which the soft plastic material or plaster compound is applied and wherein it is held during the steps of the mechanical work in the art of dentistry.

It is an object of this invention to produce 25 a tray of the character indicated which will hold the plastic material, after which, the teeth can be partially imbedded in the plastic material, and it will be unnecessary to do any trimming whatsoever.

It is a further object of this invention to produce a top or tray of the character indicated, of material similar to celluloid, thus making it possible to handle and exhibit a model without the necessity of the work required in the production of such models, as 35 is now carried on.

It is a further object of this invention to produce a top or tray of the character indicated which will be comparatively inexpensive to manufacture.

With the foregoing and other objects in view, the invention consists in the details of construction, and in the arrangement and combination of parts to be hereinafter more 45 fully set forth and claimed.

In describing the invention in detail, reference will be had to the accompanying drawings forming part of this application wherein like characters denote correspond- 50 ing parts in the several views, and in which—

Figure 1 illustrates a view in perspective of the tray for one of the jaw impressions;

Figure 2 illustrates a top plan view thereof;

Figure 3 illustrates a section on the line 55 3—3 of Fig. 2;

Figure 4 illustrates a perspective view of the tray for the impression of the other jaw;

Figure 5 illustrates a top plan view thereof; and

Figure 6 illustrates a sectional view on the line 6—6 of Fig. 5.

In these drawings, 10 denotes a top or tray having upstanding flanges forming the 65 sides of the top or tray, it being shown that the flange 11 is much higher than the flanges 12 and 13 and that the side flanges 14 and 15 are tapered in height from one end flange to the other; and furthermore, the said top 70 or tray is provided with diagonally disposed corners 17, and, as stated, this top or tray is preferably made of celluloid or some transparent material. It will be seen that the flanges 12 and 13 stand at angles to each 75 other and diagonally with respect to the side flanges.

In that form of the invention shown in Figures 4 to 6, the top or tray 18 has an end curved flange 19 at one end, and except for the configuration of this flange, the construction is the same as that of the top or tray shown in Figure 1, and therefore, a further detailed description of the same is believed unnecessary for an understanding of the invention by one skilled in the art.

I claim:

In a dental apparatus, a top or tray for plastic models comprising a one-piece structure having the character of celluloid, and the said tray including a bottom with upwardly extending flanges forming an enclosure, the said flanges being integral with one another and the bottom and continuous around the edge of the bottom, the flange at 95 one end of the tray being relatively higher than the flange at the other end thereof, and the side flanges being tapered in height from one end flange to the other.

HARRY K. VON DER HEYDT.
